UNITED STATES PATENT OFFICE.

EDWARD S. HALSEY, OF LYNN, MASSACHUSETTS, ASSIGNOR TO HALSEY MANUFACTURING CO., OF WILMINGTON, DELAWARE, A CORPORATION OF DELAWARE.

TIME-CONTROLLED THERMOSTATIC MOTOR.

1,150,185.

Specification of Letters Patent. Patented Aug. 17, 1915.

Application filed July 12, 1909. Serial No. 507,072.

To all whom it may concern:

Be it known that I, EDWARD S. HALSEY, of Lynn, in the county of Essex and State of Massachusetts, have invented certain new and useful Improvements in Time-Controlled Thermostatic Motors, of which the following is a specification.

In carrying out my invention I employ a clock with a time escapement, adapted to release, at the desired predetermined time, a tension ligament that leads from the thermostatic control to and operates, the heaters dampers, or temperature dominating valves. And is designed especially to restrain or cut out of operation a class of thermostatic devices which are motors of sufficient power and sensibility to be used to operate directly through a rod or ligament, a distant dominating heat valve, such as, the thermostatic motor described in my Patent #916,861 of March 30th, 1909, which motor has been chosen to illustrate this application.

The object of my present invention is to provide a simple effective means of simultaneously disengaging the control of the day motor thus checking the fire during the night; by a suitable timing device, that will throw said motor into commission again at a predetermined time in the morning and further to provide that while the fire is checked up, it may be engaged with and under the control of another motor designed to hold the temperature to a lower degree.

In the accompanying drawings, Figure 1 represents a front elevation of my apparatus. Fig. 2 represents a similar view on an enlarged scale of the same. Fig. 3 represents a side elevation of the same. Figs. 4 and 5 represent respectively front and rear views on a still larger scale of the time-releasing device. Fig. 6 is a side view of said device, while Figs. 7 and 8 are respectively, fractional back and side views of the mechanism, showing the sliding operating rod raised and hooked up to the time releasing stem of the clock. Fig. 9 is a sectional view looking down on Figs. 7 and 8 the section being made directly at the top of the clock. Fig. 10 shows the back arrangement of the clock when removed from the supporting frame.

Now to go into detail:—The clock is a small round time piece with a time-set

escapement located in the back portion of its case, as is quite common. To serve my purpose, the clock has the winding stem 1, of the time escapement, extended so as to project a short distance through the clock supporting metal back-plate 2. As is common in these small metal clocks, in the back a recess is formed, for the winding and set keys, by the extension of the shell of the case. In this recess a winding key 3 is fixed on said stem 1, each end of said key is recessed for the stop pin 4; which is fixed to the back of the clock, so that said key and stem can turn one-half revolution and no more and when wound up against said stop pin in the position shown in Figs. 7, 8, 9 and 10, the top side of said stem is so formed or notched that the yoke 18 which is soldered to the vertical sliding rod 6, can be hooked up on it, as shown in Figs. 7, 8 and 9, but at the time the escapement takes place the winding stem unwinds one-half turn when the other end of the key strikes the stop pin, and the notched side of said stem, looks down while its slanting face looks up as in Figs. 6 and 7, thus unhooking and letting fall the supported sliding rod 6 with the attached damper operating ligament 7.

It should be understood that the thermostatic-motors D and N used to illustrate this case are so constructed that when warmed they draw up the check damper by the connecting ligament and decrease the heat and vice-versa when cooled and that where said double thermostatic control is adopted the time mechanism is supported entirely by the night thermostat and is carried down and up in response to its every movement with the attached draft chain. When the rod 6 is raised and the cross-bar hooked on the stem 1, the temperature-controlling damper is operated directly by the night thermostat through the time mechanism and the chain 7 attached to the rod 6, the chain 9 being then slackened and the day thermostat being out of commission for the night. It should now be obvious that with the clock supporting frame 2 supported and carried by the divergent chains 8 from the night thermostat N, and with the sliding rod 6, linking ligament 9 leading from the day thermostat "D" to the check damper through ligament 7, when the escapement stem is

wound at night or other time and rod 6 is hooked up to it, chain 9 is slackened and the day thermostat thrown out of commission, while the damper and connecting rod 6 are moved up and down with the whole time mechanism, by the then controlling and supporting night thermostat "N," until rod 6 is liberated from stem 1 by the time escapement.

When no night thermostat control is desired nor provided the time releasing mechanism may be rigidly supported by being screwed to the wall, as shown in Fig. 3, in which case, when rod 6 is hooked up the heater is checked, but there is no thermostatic control until the rod is liberated and the load again falls on the single day thermostat as shown in Fig. 2.

The clock is attached to the supporting back plate 2 by hook 12, fixed at the top of the back plate which engages the hole 11 in the upper edge of the clock case frame, with the projecting stem 1 of the mechanism passing through the hole 13 in back plate 2, securing it in position, but it can readily be swung forward and then lifted off the hook to wind and set.

To cushion the fall of the rod 6 and attached damper or weights I may employ the two brass cylinders 14 and 15 made air tight at the bottom by soldering to the foot of plate 2 as shown in Figs. 5, 6 and 7, said cylinders acting as an air dash for the semi-conical, close-fitting but frictionless, flexibly mounted, piston heads 16 and 17, mounted by wire stems soldered to cross yoke 18 which in turn is soldered to the upper end of rod 6. These dash pots are not absolutely essential and may be omitted without affecting the fundamentals of the invention. The apparatus as it appears without them is shown in Fig. 3.

I am aware that time controlling devices for starting up a heater in the morning are not new.

What I claim is:—

1. In conjunction with a mechanical thermostatic motor a clock with time set escapement; an operating ligament leading from said motor to a temperature dominating valve; a device releasable by said clock mechanism at a predetermined time; for hooking up said operating ligament thereby relieving said thermostatic motor of tension and duty until released by said clock.

2. In conjunction with a mechanical thermostatic motor a clock with time set escapement, an operating ligament leading from said motor to a temperature dominating valve; a device releasable by said clock mechanism at a predetermined time; for hooking up said operating ligament thereby releasing said thermostatic motor of tension and duty until released by said clock mechanism; a second thermostatic motor designed

to operate at a different temperature from the aforesaid motor; said clock supporting device being hung from and carried up and down by said second thermostatic motor so as to be in operating control of the temperature while said operating ligament is hooked up to it by the time catch and the first said thermostat is out of commission.

3. In a heat controlling system a clock having a time set escapement; a supporting frame engaging said clock; a rod adapted to slide up and down through said frame, a stem adapted to be moved by said escapement; the projecting extremity of which is suitably shaped and located to engage and effectually support said sliding rod when in one position, and to release the rod when in another position; said stem being moved by the escapement mechanism from one said position to the other, and a heat controlling member connected to said rod.

4. In a heat-controlling system a time element; a supporting frame for said element; a vertical sliding rod working in said frame, a catch arranged to support said rod in an elevated position, operated by said time element to release the rod and permit the same to drop at a predetermined time, an air cylinder 14 closed at one end adapted to cushion the shock of said falling rod by the sudden entrance to said cylinder of the piston head 16, and a heat controlling member connected to said rod.

5. In a heat-controlling system a time element; a supporting frame for said element; a vertical sliding rod having a yoke affixed thereto working in said frame, a hook arranged to be engaged by said yoke and to support the same and the rod, in an elevated position, said hook being movable by said time element in a manner such as to release the yoke; cylinders closed at the bottom end and open at the top located beside said rod at the bottom of said frame, a piston head carried by said yoke above the cylinder and arranged to enter said cylinder and cushion the shock upon the falling of said rod, and a heat controlling member connected to said rod.

6. In a heat-controlling system, a temperature-dominating valve member adapted to occupy two or more positions, a movable controller connected with said valve member, a catch arranged to engage said controller and hold the valve member in one of its positions, said member being constantly and yieldingly urged toward another of its positions, and time-governed means for disengaging said catch from said controller.

7. In a heat-controlling system, a temperature dominating valve member adapted to be opened and closed, an endwise movable ligament for opening said valve member, a rotatable catch extending transversely into the path of movement of said ligament, hav-

ing a surface abrupt to such path of movement on one side and a surface inclined to such path on its other side, whereby the ligament may be hooked to the catch when the latter is in one position, to hold the valve member open, and time-controlled mechanism for rotating said catch.

In testimony whereof I have affixed my signature, in presence of two witnesses.

EDWARD S. HALSEY.
